US00D407694S

United States Patent [19]

Hill et al.

[11] Patent Number: Des. 407,694

[45] Date of Patent: **Apr. 6, 1999

[54] **ELECTRICAL POWER OPERATOR FOR SWITCHGEAR**

[75] Inventors: **Douglas B. Hill**, Mississauga; **Terrence S. Kerr**, Guelph, both of Canada

[73] Assignee: **S&C Electric Company**, Chicago, Ill.

[**] Term: **14 Years**

[21] Appl. No.: **82,147**

[22] Filed: **Dec. 22, 1997**

[51] LOC (6) Cl. **13-03**

[52] U.S. Cl. **D13/162**

[58] Field of Search **D13/162; 307/125**

[57] CLAIM

The ornamental design for an electrical power operator for switchgear, as shown and described.

DESCRIPTION

FIG. 1 is a perspective view of the electrical power operator for switchgear showing our new design;

FIG. 2 is another perspective view of the electrical power operator for switchgear of FIG. 1 taken from a different point of reference;

FIG. 3 is a front elevational thereof;

FIG. 4 is a rear elevational bottom plan view thereof;

FIG. 5 is a left side elevational view thereof;

FIG. 6 is a right side elevational view thereof;

FIG. 7 is a top plan view; and,

FIG. 8 is a bottom plan view.
